L. HANIFORD

RAILWAY SIGNALING DEVICE

Filed May 17, 1926

UNITED STATES PATENT OFFICE.

LOUIS HANIFORD, OF HANNA, ALBERTA, CANADA.

RAILWAY-SIGNALING DEVICE.

Application filed May 17, 1926, Serial No. 109,772, and in Canada March 30, 1926.

The invention relates to improvements in railway signaling devices and an object of the invention is to provide a device particularly adapted for use at railway crossings 5 and which is designed such that upon a train approaching the crossing, a signal will be displayed at the crossing to warn vehicular traffic that a train is approaching, such occurring in ample time to stop and thereby 10 avoid accident.

A further object of the invention is to construct the device so that a visible signal will be presented by day or night upon the train approaching and also such that an 15 audible warning such as an alarm bell will be given at the same time.

A further object of the invention is to construct the appliance such that the signal will not be released until the rear end 20 of the passing train has practically crossed the crossing.

A still further object is to arrange the signal so that it will be actuated automatically by a train approaching in either direction. 25

A still further object is to arrange and construct the parts in a simple, inexpensive and durable manner and so that they can be readily installed.

With the above more important and other minor objects in view which will become more apparent as the description proceeds, the invention consists essentially in the arrangement and construction of parts herein- 30 after more particularly described, reference being had to the accompanying drawing, in which:—

Fig. 1 is a plan view of the complete device.

Fig. 2 is an enlarged detailed vertical sectional view at 2—2' Figure 1.

Fig. 3 is an enlarged detailed vertical sectional view at 3—3' Figure 2.

Fig. 4 is an enlarged detailed vertical sectional view at 4—4' Figure 1.

Fig. 5 is an enlarged detailed vertical sectional view at 5—5' Figure 4.

Figure 6 is a view showing one of the signals in vertical section.

In the drawing like characters of refer-

ence indicate corresponding parts in the several figures.

Track rails 1 and 2 are mounted in the usual manner on the ties 3 and at the crossing there are the customary planks 4 to carry the vehicular traffic across the tracks. 55

At one side of the crossing, I locate a cross shaft 5 which extends to the sides of the tracks and has the ends thereof rotatably mounted in the side walls of similar hollow 60 casings 6 and 7 suitably mounted on the ground. Adjacent the rails, the shaft is suitably carried in similar bearing bars 8 secured to adjacent ties. Between the bearing bars, the shaft is square in cross section. 65

To the shaft I secure a comparatively wide pulley 9 and to the pulley I connect pulling lines or cables 10 and 11 of predetermined length, the cables extending along the track adjacent the rail 2 and being secured to the lower ends of similar actuating levers 12 and 13, the actuating levers being carried by cross rods 14 and 15 rotatably carried by similar bearing bars 16 secured to adjacent ties. 70

The levers which normally stand upright have their uppermost ends situated in respect to the rail 2 such that they will be struck by the flange of an oncoming train wheel and will be knocked down thereby, such movement being utilized to rotate the 75 shaft. It will be observed that the pulling line 10 passes under the pulley while line 11 passes over the top thereof.

Centrally to the shaft 5, I secure an upstanding arm 17 which is connected by a spring 18 to an adjacent tie. The ends of the shaft 5 are fitted with similar bevel gears 19 and each of these bevel gears meshes with a pinion 20 located at the lower end of a hollow shaft or pipe 21 which extends vertically 80 upwardly within the casing 6 and projects thereabove. The upper part of the casing is fashioned to provide an upper bearing for the shaft 21 and the lower end of the shaft is rotatably carried by a cross arm 22 there 85 being a collar 23 attached to the shaft and riding the cross arm and preventing down shifting of the shaft.

To the upper end of each hollow shaft 21, I secure an outstanding arm 24 which car- 90

ries a visible printed or such like signal plate 25 and the arrangement of the parts is such that these signal plates are normally in closed position extending transversely of the track when the levers 12 and 13 are in an upright position and such that when the levers are struck down by an approaching train, such movement will cause a sufficient rotation of the shaft 5 to bring the stop plates into a position across the highway. Consequently the opened signal plates will visibly indicate in the daytime and to vehicular traffic that a train is approaching.

The distance which the levers 12 and 13 are away from the crossing will be determined by experience, it being obviously desirable that the signals should be turned to warning position in ample time before the train reaches the crossing. It is necessary also to lock the signals in the open or warning position immediately after they have been opened by the striking of one of the levers and to this end I have provided parts shortly described.

25 Adjacent the rail 1, I locate a pressure bar 26 which has a flange 27 directly opposite the head of the rail and which is provided with three socket like extensions 28, 29 and 30, the extensions slidably receiving 30 similar stationary ground guides 31. A coiled spring 32 is inserted in each socket like extension and operates to maintain the pressure bar normally in a position such that the flange thereof is level with the upper face of the rail head as best shown in Figure 5. The ends of the pressure bars are downturned so that the flange of the passing car wheel will readily ride up onto the pressure bars and depress the same.

40 To the shaft 5 I secure a dog 33 which, in the rotation of the shaft under the influence of either of the actuating levers, is adapted to move up and become caught on the projecting end of a catch bar 34 resting on the base of a suitable cross slot 35 formed in the face of the adjacent tie. A housing 36 encloses the top and one end of the slot and retains a spring 37 which rides the catch bar and normally holds the same in the position best shown in Figure 4.

45 It will be observed in this figure that the left hand end of the catch bar is free to rise against the action of the spring whilst the right hand end which projects beyond the housing is held against rising by the housing. The catch bar is actually free to tilt upwardly when struck by the dog with the result that when the dog has clicked past the adjacent end of the catch bar, it becomes locked in a substantially horizontal position by the catch bar. In this connection, I might point out that when the dog is so locked, the spring 38 is extended.

50 The tubular extension 29 is provided with 60 a lug 29' which normally overlies the adja-

cent projecting end of the catch bar. According to the above description it will be obvious that when say the lever 12 is struck down by the approaching train, the shaft is rotated to swing the signals to warning 70 position across the roadway and that immediately they reach this position, they are locked by the dog 33 becoming caught on the catch bar. The signals will accordingly remain in locked open position until otherwise released.

When the advancing train reaches the pressure bar 26, the pressure bar will be moved down under the action of the wheel flange and the lug 29' will tilt the catch bar 80 so that the end adjacent the dog will go up far enough to let the caught dog escape past thereby unlocking the shaft 5 and permitting the signal plates to swing to the closed position. I might here mention that the 85 signal plates are set back far enough so that they will not strike the passing train and further I might point out that as the front end of the train is at this time on the crossing there is no likelihood of an accident 90 occurring as one would not attempt to drive onto a crossing where the engine was at the crossing.

As the parts reset, the lever 13 will go back to the vertical position and will be 95 struck by the train but this will simply be an idle movement as it will cause a slackening of the cable 11.

Obviously the action of opening the stop signals to warn traffic will be the same as 100 that just described when the train is approaching the crossing from the side where the lever 13 is installed. Both levers are fitted each with a weight 38 which acts to take up any slack occurring in the cable. 105

The signs or signal plates will of course be quite visible on clear days but it is also desirable for night use or inclement days that those approaching the crossing be warned not only by an illuminating light 110 but also by an alarm. To this end I have located a suitable source of electromotive force such as a battery 39 in each casing or box 6 and have grounded one side of the battery and have connected the other side thereof by a flexible wire 40 to a contact point 41 carried by an insulated arm 42 secured to the shaft 5. The contact point 41 in the rotation of the shaft is adapted to make contact with an insulated spring arm 43 suitably mounted in each casing 6. An insulated wire 44 leads from each contact spring 43 upwardly through the hollow shaft and connects with one of the terminals of an electric lamp 45, the other terminal of the 125 lamp being ground to the shaft. An electrical alarm or gong 46 is carried by the shaft and is connected in series with the lamp. A transparent lamp globe 47 encloses the lamp. 130

The contact points 41 are adapted to engage the spring contacts when the signal plates 25 have been swung across the vehicle roadway with the result that the gong gives an audible alarm and the light is illuminated so that one is very positively warned regardless of weather conditions and during both day and night that a train is approaching.

Whilst I have entered into a detailed description of the various parts, it will be understood that they could be modified without departing from the spirit of the invention as set forth in the appended claims.

What I claim as my invention is:—

1. A railway signaling device for use on highway crossings comprising a rotatably mounted shaft located at the crossing and extending transversely of the crossing and there beyond, upright rotatably mounted spindles located at the ends of the shaft, intermeshing gears and pinions connecting the shaft to the spindles, a signal carried by each spindle and extending normally parallel with the highway but clear of the tracks, a depressible member located at each side of the crossing and at some distance there from and adjacent one of the rails and adapted to be depressed by an on coming train, means connecting said members to the shaft whereby in the depression of either member the shaft is rotated in a direction to swing the signals transversely of the highway, means for automatically locking the signals in such latter positions, depressible unlocking means located at the crossing, said unlocking means being adapted upon depression to release the locking means and free the signals and means for returning the freed signals to their initial position.

2. A railway signaling device for use on highway crossings comprising a rotatably mounted cross shaft, located at the crossing, crossing the tracks and extending there beyond, vertically disposed spindles located at the ends of the shaft, intermeshed gears and pinions carried by the shaft and spindles, a signal secured to each shaft and normally disposed in a direction parallel with the highway but clear of the tracks, a depressible member located at each side of the crossing and at some distance therefrom and adjacent one of the track rails and adapted to be depressed by a train approaching the crossing, means connecting each depressible member with the shaft whereby in the depression of the member, the shaft is rotated to turn the signals simultaneously across the highway, means associated with the shaft for automatically locking the shaft against rotation when the signals are brought to the latter position, a depressible device and spring means for returning the unlocked signals to their initial position.

locking device and spring means for returning the unlocked signals to their initial position.

3. A railway signaling device for use on highway crossings comprising a rotatably mounted cross shaft, located at the crossing, crossing the tracks and extending there beyond, vertically disposed spindles located at the ends of the shaft, intermeshed gears and pinions carried by the shaft and spindles, a signal secured to each shaft and normally disposed in a direction parallel with the highway but clear of the tracks, a depressible member located at each side of the crossing and at some distance therefrom and adjacent one of the track rails and adapted to be depressed by a train approaching the crossing, means connecting each depressible member with the shaft whereby in the depression of the member, the shaft is rotated to turn the signals simultaneously across the highway, means associated with the shaft for automatically locking the shaft against rotation when the signals are brought to the latter position, a depressible member adjacent the crossing and adapted to be engaged with the wheel of the passing train and designed when depressed to release the locking device, spring means for returning the unlocked signals to their initial position and an audible alarm operating coincidently with the signals and adapted to give an audible warning during the interval that the former signals are across the highway.

4. A railway signaling device for use on highway crossings comprising a rotatably mounted shaft crossing the tracks adjacent the crossing and extending there beyond, upright spindles located at the ends of the shaft and rotatable therewith, signals secured to the spindles and extending normally parallel with the highway and clear of the tracks, depressible actuating levers located at either side of the crossing and at some distance therefrom and adjacent one of the track rails, operating lines connecting the levers with the shaft whereby the depression of either lever by an on coming train rotates the shaft and turns the signal into a direction transversely of the highway, means locking the shaft against rotation upon the signals reaching the latter position, a depressible bar adjacent one of the tracks and engageable with said locking means and adapted to be depressed by the train at the crossing and upon depression to release the locking means and spring means for rotating the released shaft to its initial position.

5. A railway signaling device for use on highway crossings comprising a rotatably mounted shaft extending transversely of and beyond the crossing, casings receiving the ends of the shaft therein, upright spindles

rotatably journaled in said casings and carrying suitable visible signals, a gear drive between each spindle and the adjacent end of the shaft, an audible signal mounted in each casing, a lamp carried by each spindle and connected in series with said audible signal and an automatic switch included in the lamp and audible signal cir-

cuit and contained in said casing, said switch including an insulated contact carried by said shaft and engageable and disengageable with a spring contact carried by the casing. ¹⁰

Signed at Hanna this 1st day of March, 1926.

LOUIS HANIFORD.
